UNITED STATES PATENT OFFICE

DAVID MICON, OF MILWAUKEE, WISCONSIN
MATTRESS AND METHOD FOR MAKING SAME

Application filed January 21, 1928. Serial No. 248,282.

This invention relates to mattresses. Mattresses of the type which has been in general use heretofore have usually had the top and bottom drawn together by twine extending through the filling of the mattress to compress the filling with tufts attached to the twine outside the mattress. Such a construction necessitates providing openings in the mattress cover which are adapted to be come larger in use and through which dirt and vermin may readily reach the interior of the mattress. The primary object of this invention is to provide a mattress in which no such holes result in the cover of the mattress.

Another object of this invention is to provide a mattress and method for making the same whereby the top and bottom are conveniently secured together to compress the filling by an improved means wholly within the cover.

Another object of this invention is to provide a mattress which is simple of construction and economical to manufacture.

Other and further objects of this invention will be apparent as the same becomes better understood from an examination of the accompanying drawings wherein:

Fig. 1 is a perspective view of a portion 30 of a finished mattress,

Fig. 2 is a vertical section on the line 2—2 of Fig. 1,

Fig. 3 is an enlarged detail view showing one of the steps which are used to form 35 the loops which are attached to the inside of the mattress and by means of which the top and bottom of the mattress are secured together.

Fig. 4 is a similar view illustrating how 40 the strips forming the loops are twisted before being attached to the mattress cover,

Fig. 5 is a similar view illustrating how the strips are bent after being twisted,

Fig. 6 is a perspective view illustrating 45 how the strips are attached to the inside of the mattress cover,

Figs. 7—10, inclusive, are enlarged fragmentary vertical sectional views of the mattress illustrating some of the steps in the manufacture of the mattress, and

Fig. 11 is an enlarged detail view partly in section illustrating the manner of attaching the upper end of one of the cords to the upper loop for securing the top and bottom of the mattress cover together. 55

Referring to the drawings more particularly, numeral 1 indicates the top, 2 the bottom and 3 the sides of a mattress cover or tick which may be filled with any suitable material but which is here illustrated as 60 filled with a plurality of springs 4 inclosed in cotton batting 5. The springs 4 are arranged with their axes vertical whereby they may resist compression of the mattress.

The top and bottom of the mattress are 65 secured together to compress the filling by means of a plurality of cords 6 which are attached respectively to oppositely disposed loops 7 attached to said top and bottom at 70 points spaced longitudinally and transversely thereof.

The loops 7 are each formed of a single strip 8 which is twisted one or more times intermediate its ends as shown in Fig. 4. 75 The ends of the strip 8 are then brought together as illustrated in Fig. 5 and sewed flat against the inside of the cover. In order that the strain of the cord 6 may be distributed over as large an area as possible of the cover to which the strip 8 is attached, 80 the strips are attached to the cover by sewing a strip 9 transversely across each of them. The twist 11 invariably occurs centrally of the strip 8 whereby it will be located at the outer end of the bight formed 85 thereby. This causes the effective width of the strip to be considerably reduced at the end of the bight and to be increased gradually to normal from said end to the point where the strip is attached to the cover. The cord 6 being attached to the loop at the end 90 of the bight thereof the strain of said cord is distributed uniformly throughout the width of the strip to the strip 9.

In the manufacture of the mattress the filling is placed on a table 12 which is provided with a plurality of holes 13. The mattress cover is applied to the filling in two sections, first, the bottom 2 with the sides 3 attached 100

and then the top 1 is applied and sewed to the upper edges 14 of the sides 3.

Both the top 1 and the bottom 2 are provided with the loops 7 previously described before the cover is applied to the filling. It will be seen from the drawings that each of the cords 6 consists of a length of twine or cord which has been doubled back along its length to form a bight 15 and the two strands 16 and 17. As shown in Fig. 6 each of the cords 6 is attached to its respective lower loop 7 by simply passing it through the loop and through the bight 15 and then tightening up on said cord to bring said bight up close to said loop. After all of the cords have been thus secured to their respective lower loops 7, the bottom 2 is applied to the filling.

As shown in Figs. 7 and 8 the bottom 2 is applied to the filling by drawing said bottom over the filling and pulling the cords 6 through the same by means of a needle 18. In practice the bottom is drawn over the filling to the first row of loops, the cord 6 on each of these loops is drawn downwardly through the filling by extending the needle 18 upwardly through the respective hole 13 and the filling, passing the end of the cord through the eye of the needle and withdrawing the needle downwardly. The bottom 2 is then drawn over the filling to the next row of loops and the process repeated until the bottom has been drawn completely over the filling and all of the cords 6 have been drawn through the filling to the opposite side there-of.

The filling of the mattress with the bottom of the cover applied thereto is then inverted on the table and the top 1 of the cover applied.

40 The top 1 is applied by drawing the same over the mattress filling and attaching the ends of the cords 6 to the loops. In practice the top 1 is drawn over the top of the filling to the first row of loops. Each cord 45 is attached to its respective loop by passing its end through the loop and then through the standing part 19 of the cord between the two strands 16 and 17 thereof separating the two strands of the end after passing the same 50 through the standing part and passing them back around the opposite sides of said part and bringing them together at first in a single twist or ordinary overhand knot 21. The cord is then tightened to compress the filling 55 including the springs by drawing on the two strands of the cord beyond the twist.

The aforescribed arrangement with or without the single twist knot permits the springs to be compressed by tightening the 60 cord by drawing on the end thereof but does not permit the cord to slip back through the loop before the knot has been completed. When the cord has been thus tightened, the knot is completed by adding one or more 65 additional twists as at 22 to hold the springs

in compressed position. After each of the loops in the first row have been secured to their respective cords 6 in this manner, the top 1 is drawn over to the next row of loops and the process is repeated until the entire top has been drawn over the filling and all of the loops have been secured. 70

After the top and bottom of the cover have been secured together as described, the edge of the top is sewed to the upper edge 14 of the sides 3 as described and the rolls 23 and 24 are provided in the usual manner to the top and bottom respectively of the mattress. 75

It will be apparent that the aforescribed method particularly the manner in which the cords 6 are secured to the upper loops enables the top and bottom of the mattress cover to be drawn together sufficiently to properly compress the filling including the springs of the mattress in a convenient manner. 80 85

I am aware that many changes may be made without departing from the principles of this invention and I therefore do not wish to be limited to the details shown or described. 90

I claim:

1. The method of making a mattress which comprises providing the horizontal sides of the mattress cover with oppositely disposed loops, attaching a cord to all of the respective loops on one side, applying said side to the filling of the mattress by drawing the free ends of the respective cords through the filling, and applying the other side of the cover to the filling by attaching said ends to the corresponding loops on the latter side and then securing the edges of the two sides of the cover together. 95 100

2. The method of making a mattress which comprises providing the horizontal sides of the mattress cover with oppositely disposed loops, applying the sides of the mattress to the mattress filling and connecting the respective opposite loops by a double strand cord by attaching one end of the cord to one loop drawing the free end through the filling and passing it through the other loop and then through the standing part of the cord between the two strands thereof, separating the two strands of said end after passing the same through the standing part and passing them back around the opposite sides of said part bringing them together in a single twist knot tightening up on the cord to compress the filling by drawing on the two strands beyond the twist and completing the knot with one or more additional twists to secure the mattress in compressed condition. 110 115 120

3. The method of making a mattress which comprises providing the horizontal sides of the mattress cover with oppositely disposed loops, attaching a cord to all of the respective loops on one side, applying said side to the filling of the mattress by drawing the free ends of the respective cords through the filling, 115 120 125

and applying the other side of the cover to the filling by attaching said ends to the corresponding loops on the latter side.

4. The method of making a mattress which comprises applying the horizontal sides of the mattress cover to the mattress filling by connecting the respective sides by a double strand cord by attaching one end of the cord to the inner surface of one side of the cover drawing the free end through the filling and passing it through a loop on the inner surface of the other side and then through the standing part of the cord between the two strands thereof, separating the two strands of said end after passing the same through the standing part and passing them back around the opposite sides of said part bringing them together in a single twist knot tightening up on the cord to compress the filling by drawing on the two strands beyond the twist and completing the knot with one or more additional twists to secure the mattress in compressed condition.

5. A mattress comprising a cover having top, bottom and a filling therefor, and means including loops attached to said top and bottom and cords connecting the loops whereby the top and bottom are secured together to compress said filling, each loop consisting of a folded and twisted fabric strip having its ends attached to the cover, the twist occurring at the outer end of the loop, the cords being attached to the respective loops at the twist whereby each strain of the cord is distributed evenly to the attached ends of the loop throughout the width of the strip.

6. A mattress comprising a cover having top, bottom and a filling therefor, and means including loops attached to said top and bottom and cords connecting the loops whereby the top and bottom may be secured together to compress said filling, the respective loops each formed of a strip which is twisted and bent to provide a bight, the twist occurring at the outer end of the bight and the ends sewed flat against the inner surface of the cover, the cords being attached to the respective loops at the twist whereby the strain of the cord is distributed evenly to the other end of the bight throughout the width of the strip.

7. The method of making a mattress which comprises attaching a plurality of cords at spaced points respectively to the inner surface of one of the horizontal sides of the mattress cover, applying said side to the filling of the mattress by drawing the free ends of the respective cords through the filling and applying the other side of the cover to the filling by attaching said ends to the inner surface of the latter side and then securing the edges of the two sides of the cover together.

8. The method of making a mattress which comprises attaching a plurality of cords at spaced points respectively to the inner surface of one of the horizontal sides of the mattress

cover, applying said side to the filling of the mattress by drawing the free ends of the respective cords through the filling and applying the other side of the cover to the filling by attaching said ends to the inner surface of the latter side. 70

9. A mattress comprising a tick and a filler, oppositely disposed loops attached to the inner faces of the top and bottom of the tick, each of said loops comprising a fabric strip 75 twisted intermediate its ends and folded upon itself, the ends being secured to the tick, and cords connecting the respective loops whereby the top and bottom are secured together.

In witness of the foregoing I affix my signature. 80

DAVID MICON.
